US00D894958S

(12) **United States Design Patent** (10) Patent No.: **US D894,958 S**
(45) Date of Patent: **** Sep. 1, 2020**

(54) **DISPLAY SCREEN OR PORTION THEREOF WITH ICON**(71) Applicant: **Palantir Technologies Inc.**, Palo Alto, CA (US)(72) Inventor: **Piotr Kwiatkowski**, London (GB)(73) Assignee: **PALANTIR TECHNOLOGIES, INC.**, Palo Alto, CA (US)(**) Term: **15 Years**(21) Appl. No.: **29/715,607**(22) Filed: **Dec. 3, 2019****Related U.S. Application Data**

(63) Continuation of application No. 29/594,107, filed on Feb. 15, 2017, now Pat. No. Des. 868,827.

(51) **LOC (12) Cl.** ..... **14-04**(52) **U.S. Cl.**USPC ..... **D14/489**(58) **Field of Classification Search**

USPC D14/489-493

CPC G06F 3/04817; H04N 1/00424

See application file for complete search history.

CLAIM

The ornamental design for a display screen or portion thereof with icon, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the U.S. Patent and Trademark Office patent file or records, but reserves all other copyrights whatsoever.

The FIGURE is a front view of a display screen or portion thereof with icon showing my new design.

The broken lines in the figure represents a display screen or portion thereof and form no part of the claimed design.

1 Claim, 1 Drawing Sheet© 2016 Palantir Technologies, Inc.
